Primary Examiner — Susan E Krakower*Assistant Examiner* — Christina M. Dodson(74) *Attorney, Agent, or Firm* — Sang Young Han**(57) CLAIM**

The ornamental design for an astronaut starry sky projector, as shown and described.

DESCRIPTION

FIG. 1 is a front elevation view of an astronaut starry sky projector, showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front and top perspective view thereof; and,

FIG. 8 is a rear and bottom perspective view thereof.

The features shown in light grey, deemphasized shading, depict portions of the article that form no part of the claimed design.

1 Claim, 8 Drawing Sheets(56)
